UNITED STATES PATENT OFFICE.

THOMAS J. LEWIS, OF NEW YORK, N. Y.

HAND BAG FOR LADIES.

Application filed August 31, 1925. Serial No. 53,559.

This invention relates to improvements in hand bags, or like articles for ladies, and it is the principal object of the invention to provide a hand bag having a number of 5 pockets or compartments for the convenient carrying of a number of articles to be used by ladies, such as cigarettes, powder puff, mirror, cards, bills and small change, etc., which allows a ready use of these articles 10 when desired, while the entire bag takes up a very limited space and can conveniently be suspended from the arm, etc., of the wearer.

Another object of the invention is the provision of a securely closed bill fold 15 secured to the inner face of the closing flap of the bag, allowing a separation of bills of various denominations.

A further object of the invention is the provision of a lady's hand bag comprising a 20 sleeve of ornamental material in which an inner compartment for the reception of cigarettes is slidably arranged for limited movement, to be extracted by a pull on a tassel.

25 A still further object of the invention is the provision of a hand bag for ladies, comprising a sleeve allowing the carrying of calling cards and a name plate on its front.

It is also one of the objects of the invention to provide a lady's hand bag in form 30 of a sleeve which contains slidably arranged therein within certain limits a number of compartments or pockets for the reception of small change, powder puff, a mirror, etc., adapted to be ready for use by a simple pull 35 on a band.

These and other objects and advantages of my invention will become more fully known, as the description thereof proceeds, and will 40 then be specifically defined in the appended claims.

In the accompanying drawings, forming a material part of this disclosure:

Fig. 1 is a front elevation of my novel 45 hand bag constructed according to the present invention, closed.

Fig. 2 is a view similar to Figure 1 with the hand bag open.

Fig. 3 is a front elevation of the hand bag 50 open and partially extended with open bill-fold.

Fig. 4 is a view similar to Figure 3 with the hand bag extended, showing the mirror, the change pocket, etc.

Fig. 5 is a longitudinal section on line 55 5—5 of Fig. 1.

Fig. 6 is a longitudinal section on line 6—6 of Fig. 4.

Fig. 7 is a cross-section on line 7—7 of 60 Figure 4.

Referring to the drawings, in which like reference numerals are used to denote corresponding parts throughout the several views, 10 denotes the body of the bag which here has the form of a sleeve open at both 65 ends and covered by any suitable fancy or ornamental material.

In this sleeve or body, a member 11 is arranged, adapted to be displaced in longitudinal direction and prevented from being 70 accidentally entirely withdrawn from the body by means of elastic bands 12, 13.

The upper part 14 of member 11 is adapted to be folded along a line 15 upon the outer face of sleeve 10 to cover the outer face thereof, and carries at its upper end a snap button 16, adapted to engage a socket 17 on the outer face of sleeve 10 near the lower end thereof.

A double handle strap 18 or the like is attached at its lower ends forming loops 19, to rings 20 or the like attached to the upper end of body 10, while loops 21 hold the two parts of the strap 18 together.

The part 14 has attached to its inner face 85 a bill-fold 22, comprising a plurality of pockets 23 adapted to be closed by a flap 24 equipped on its inner face with a snap button 25 adapted to engage a socket 26 on bill-fold 22.

The lower part of member 11 is formed 90 into a compartment 27 having a lateral opening 28, the walls of which are somewhat curved, as illustrated in Figure 4, and which serves for the reception of cigarettes, etc. A 95 tassel 29 formed into a fancy knot 30 is attached to the lower end wall of compartment 27 by means of a short cord 31 which acts as a draw or pull cord when it is desired to slide compartment 27 out of the lower end 100 of sleeve 10 to fill or extract cigarettes, etc., with or from said compartment.

Below the fold line 15 a pocket 32 is formed with the inner face of member 11, for the reception of a powder puff, or other articles of a lady's toilette, and the front wall of said pocket is extended to form a flap 33 covering a pocket 34 for small change 105

- etc. The flap 33 carries on its inner face a socket member 35 adapted to be engaged by a snap button 36 when the flap 33 is lowered to close pocket 34.
- 5 Near the lower end of pocket 34 a pull strap 37 having an armored end 38, is attached for pulling compartment 27 into sleeve 10 and pockets 32 and 34 upwardly to give access to the same.
- 10 A mirror 39 is attached to the inner face of the wall 40 of compartment 27 adapted to extend over the upper edge of sleeve 10 so that the mirror, when it is to be used will be exposed by turning over the edge of sleeve 10 with its rear engaging the outer face of said sleeve as indicated in Figure 6. The upper end of compartment 27 is closed by the material of member 32, as indicated at 41.
- 15 The outer upper face of sleeve 10 is formed with a card-case 42 for the reception of a number of calling cards, etc., and a window 43 is formed below frame 42 for a name plate, etc.
- 20 The operation of my device will be entirely clear from the above description; if it is desired to use the lower compartment 27 to extract a cigarette therefrom through its lateral opening 28, a pull on tassel 29 will slide this compartment to a suitable distance out of sleeve 10, while the elastics 12 and 13 will limit this movement. An extraction of bills from the bill-fold 22 will conveniently be allowed by opening and folding back flap 35 14, and opening flap 24 of the bill fold.
- If a use of power puff, small change or of the mirror is desired, a pull on band 37 will slide the same out of the upper end of sleeve 10 to the desired distance also limited by elastics 12 and 13, and the mirror will by its own weight, fall into the proper position indicated in Figure 6. When closed, the upper part 14 will cover the front face of sleeve 10 and be locked thereto by means of snap lock 16, 17 while the bag can be conveniently suspended from the arm or clothing by means of strap 18.
- 25 It is to be understood that the practical embodiment of my invention shown as an example of its preferred form on the drawings, will allow many changes in its general arrangement and in the construction of its minor details, such as fall within the scope of the appended claims without departure from the spirit of the invention and the principle involved.
- Having thus described my invention, what I claim as new and desire to secure by Letters Patent, is:
- 30 1. A lady's hand bag comprising a sleeve, a sliding member held on said sleeve for limited movements in either direction, the upper part of said member adapted to be folded over said sleeve to form a cover for the same, a means for locking said cover to said sleeve, a bill fold having a plurality of pockets within the upper part of said member, means for closing said bill fold, means for pulling said member out of the lower part of said sleeve, and a means for displacing said member within said sleeve to project above the upper edge of same.
- 35 2. In a lady's hand bag an open sleeve, a sliding member within said sleeve, having an upper part adapted to fall over said sleeve to form a cover for the same, a means for limiting the movement of said member, a bill fold formed with the upper part of said member, a pocket for the reception of a powder-puff formed with said member below its upper part, a change pocket in front of said first named pocket, a closing flap for said change pocket, an armored band for pulling said member out of the upper part of said sleeve, and a mirror normally engaging said change pocket, and secured to said member at one end adapted to fall over the upper edge of said sleeve when said member is extracted to display the glass, and a handle for said hand bag.
- 40 3. The combination of an open sleeve with a sliding member within the same for forming a lady's hand bag and vanity case, said sliding member forming a flap cover for said sleeve, a means for locking both parts together, a means for limiting the relative movement of said member and sleeve, a handle on said sleeve, the lower part of said member constituting a pocket or case for cigarettes, a tassel secured to said case for pulling said case out of the lower end of said sleeve for allowing access to said case, a bill-fold, having a plurality of pockets formed with the upper part of said member on the inner face thereof, a closing flap for said bill fold, a pocket formed with the inner face of said member below said bill fold, a small change pocket provided on the outer face of said first named pocket, a mirror attached at one end to said member, and an armored band for drawing said mirror out of the upper end of said sleeve for allowing access to said pocket and for allowing said mirror to drop over the upper edge of said sleeve to display its glass, said sleeve having a card-case formed on its outer face, and a means for the reception of a name plate below said case.
- 45 Signed at New York, in the county of New York, and State of New York, this twenty-seventh day of August A. D. 1925.
- 50 110 THOMAS J. LEWIS.
